CLAIM

The ornamental design for a mirrored dispenser container, as shown and described.

DESCRIPTION

FIG. 1 is a top perspective view of a mirrored dispenser container, showing my new design, in a closed state;

FIG. 2 is a front side view thereof;

FIG. 3 is a rear side view thereof;

FIG. 4 is a right side view thereof;

FIG. 5 is a left side view thereof;

FIG. 6 is a top plan view thereof;

FIG. 7 is a bottom plan view thereof; and,

FIG. 8 is a top perspective view thereof, in an open state.

In some embodiments, the portions of the mirrored dispenser container shown in FIGS. 1 to 7 are made of metal such that at least the rib edge portion around the periphery of the lid has a metallic color.

In some embodiments, the substantially rectangular portion on the interior upper wall that is exposed upon opening the lid to the position shown in FIG. 8 is reflective or a mirror.

In some embodiments, the underside of the lid is reflective or a mirror such as to present such underside upon opening into the configuration shown in FIG. 8.

In some embodiments, the dispensing opening shown exposed in the open state in FIG. 8 at a lower corner of the upper wall is formed into the shape of a circle, or an ellipse, or a rectangle, or another shape.
